UNITED STATES PATENT OFFICE.

HENRY A. W. SMITH, OF CHATHAM, VIRGINIA.

SHEARS.

1,359,762.

Specification of Letters Patent. Patented Nov. 23, 1920.

Application filed March 1, 1919. Serial No. 279,946.

To all whom it may concern:

Be it known that I, HENRY A. W. SMITH, a citizen of the United States, residing at Chatham, in the county of Pittsylvania and 5 State of Virginia, have invented a new and useful Shears, of which the following is a specification.

The device forming the subject matter of this application is a pair of shears, and the 10 invention aims to provide an improvement in the pivotal connection between the blades of the shears, the end in view being to provide pins, which as distinct elements, may be mounted in the nut, and in a sleeve which 15 forms a pivotal connection between the blades of the shears, to prevent relative rotation between the sleeve and the nut while the bolt which engages the nut is being tightened up.

20 It is within the province of the disclosure to improve generally and to enhance the utility of devices of that type to which the invention appertains.

With the above and other objects in view, 25 which will appear as the description proceeds, the invention resides in the combination and arrangement of parts and in the details of construction hereinafter described and claimed, it being understood that, with- 30 in the scope of what is claimed, changes in the precise embodiment of the invention shown can be made without departing from the spirit of the invention.

In the accompanying drawings:—

35 Figure 1 shows in plan, a pair of shears constructed in accordance with the invention; Fig. 2 is a section on the line 2—2 of Fig. 1; Fig. 3 is a section on the line 3—3 of Fig. 2; Fig. 4 is a plan of the nut; and 40 Fig. 5 is a section corresponding to Fig. 2 but disclosing a modification.

Referring to Figs. 1 to 4, both inclusive, there is shown a pair of shears comprising a blade 1 and a blade 2, the blade 2 having 45 an opening 3, and the blade 1 having an opening 4. A tubular sleeve 5 is mounted in the openings 3 and 4 and is supplied in one end with seats 6. A bolt 7 passes through the sleeve 6 and includes a head 8 coöperating with the blade 2, the blade 8 having a screw driver kerf 9. The numeral 10 marks a nut having seats 11 wherein the outer ends of pins 12 are fixed, the inner ends of the pins being adapted to be received 50 in the seats 6 of the sleeve 5.

In practical operation, the pins 12, which are carried by the nut 10, are received in the seats 6 of the sleeve 5, the bolt 7 is passed through the sleeve 5 and the bolt is threaded into the nut 10, the nut being held against 60 rotation, by means of the pins 12, until the bolt is rotated so that its head 8 coöperates with one end of the sleeve 5 and with the outer surface of the blade 2, the nut 10 being drawn down upon the blade 1. In this connection it is to be observed that, as indicated at 14, one end of the sleeve 5 is spaced from the outer surface of the blade 1, so that the bolt can be tightened up any desired degree 65 in the nut 10 without engaging the adjacent 70 end of the sleeve 5.

The construction of the device is such that the pins 12 may be fashioned as elements independent of the sleeve 5 and the nut 10, and be fixed in the nut. 75

In Fig. 5 of the drawings, a modified form of the invention has been shown. In the said figure, parts hereinbefore described have been designated by numerals previously used, with the suffix "a." In this form of 80 the invention, the pins 12^a are seated fixedly in the recesses of the sleeve 5^a and are received removably in the recesses or seats 11^a of the nut 10^a.

Having thus described the invention, what 85 is claimed is:—

A pair of shears including blades; co-operating elements comprising a tubular sleeve forming a pivotal connection between the blades, and a nut at one end of the sleeve 90 and coacting with one blade; a bolt extended through the sleeve, the bolt and the nut having continuous coacting threads, the bolt having a head coacting with the other blade, both of said coöperating elements having 95 seats spaced respectively from the bore of the sleeve and from the bolt-receiving opening of the nut, whereby the threads may be continuous as aforesaid; and pins fixed in the seats of one of coöperating elements and 100 received removably in the seats of the other of said coöperating elements.

In testimony that I claim the foregoing as my own, I have hereto affixed my signature in the presence of two witnesses.

HENRY A. W. SMITH.
